THE NORRIS PETERS CO., PHOTOLITHO., WASHINGTON, D. C.

UNITED STATES PATENT OFFICE.

WILLIAM S. DOIG, OF NEW YORK, N. Y.; EMMA DOIG EXECUTRIX OF SAID
WILLIAM S. DOIG, DECEASED.

BOX-MAKING MACHINE.

SPECIFICATION forming part of Letters Patent No. 663,223, dated December 4, 1900.

Application filed May 7, 1898. Serial No. 680,050. (No model.)

To all whom it may concern:

Be it known that I, WILLIAM S. DOIG, a citizen of the United States, residing in New York city, borough of Brooklyn, New York, have invented certain new and useful Improvements 5 in Box-Making Machines, of which the following is a specification.

This invention relates to improvements in box-making machines, and more particularly 10 to the class of machines adapted for making circular boxes, such as those adapted for containing cheese, which boxes have a circular head and an annular side made from a strip or band of wood nailed to said head, the overlapping portions of said strip or band being nailed or tacked together.

The invention consists in a box-making machine comprising a frame, a box-side former rotatively carried thereby, a gate connected 20 with said frame, means carried by said gate for clamping a box-head to said former, means for rotating said head and former, and means for driving nails into the box side and for nailing the box to said head.

25 The invention further consists in a box-making machine comprising a frame, a box-side former rotatively carried thereby, a gate pivotally connected with said frame, means for clamping a box-head to said box-side former, a guide located beneath said former adapted to hold the box-head in position 30 against the former, and means for nailing the overlapped portions of the box side together and the box side to said head.

35 The invention further consists in a box-making machine comprising a frame, a horizontal shaft carried thereby, a box-side former carried by said shaft and comprising means for increasing and decreasing its diameter, 40 said shaft being adjustably held to enable its location to be altered, means adjustably carried by said frame for clamping a box-head to said former, whereby said means may be aligned with said shaft in the different positions of the latter, means for rotating said box-head when clamped to said box-side former, and means for nailing the overlapped portions of the box side together and the box side to said head.

45 The invention also consists in a nailing device comprising a support, a nail-box carried

thereby and having a pair of pivoted jaws and bores leading thereto, one of said bores being adapted to receive a nail, a plunger adapted to reciprocate in the other bore, 55 means for operating said plunger, and means for holding said jaws closed.

The invention also consists in the novel details of improvement and the combinations of parts, that will be more fully hereinafter set 60 forth and then pointed out in the claims.

Reference is to be had to the accompanying drawings, forming part hereof, wherein—

Figure 1 is an end elevation of a box-making machine embodying my improvements. Fig. 2 is a side elevation thereof looking from the left in Fig. 1. Fig. 3 is a view similar to Fig. 2 looking from the right in Fig. 1. Fig. 4 is a vertical longitudinal central section, enlarged, through the main parts of the machine. 70 Fig. 4^a is a detail face view of the worm-plate for adjusting the diameter of the box-side former, taken on the line x x in Fig. 4, looking in the direction of the arrows. Fig. 4^b is a perspective view of the guide 168. Fig. 5 75 is an enlarged vertical cross-section of the main operative parts of the machine, showing the strip or band wound upon the box-side former and showing also the devices for nailing the overlapping portions of the box side together and for cutting off the surplus material. Fig. 6 is an enlarged detail front view of the main part of the nailing devices. Fig. 7 is a vertical section on the line y y in Fig. 6. Fig. 7^a is a perspective view of the knife holding 80 means. Fig. 8 is a detail cross-section on the plane of line 8 8 in Fig. 7. Fig. 9 is a similar view on the plane of the line 9 9 in Fig. 7. Fig. 10 is a side elevation of the nailing devices that are shown used in connection with 90 this machine. Fig. 11 is a plan view thereof. Fig. 12 is an enlarged detail plan view showing the connection between the tilting nail-pau and its stationary chute. Fig. 13 is a front elevation of the nail-selecting devices, 95 and Fig. 14 is a section on the line 2 2 in Fig. 13.

In the accompanying drawings, in which similar numerals and letters of reference indicate corresponding parts in the several views, 1 indicates generally the main frame 100 of the machine, which may be of suitable construction.

2 is a shaft arranged horizontally in frame 1 and carried in suitable bearings 3 therein in such manner that it can rotate. The bearings 3 are shown in the form of boxes that are 5 adapted to be raised and lowered to alter the position of shaft 2, for a purpose that will be described hereinafter. The shaft 2 carries the box-side former or head upon which a band or strip of wood 4 is adapted to be wound to 10 form the circular side of the box. (See Fig. 5.) This box-side former is shown composed of a plurality of segmental plates or strips 5, having their convex surfaces extended outwardly and being located parallel to shaft 2, 15 and these plates or strips are carried by arms 6, that are suitably connected with said shaft. The outer surfaces of the plates 5 are all at equal distances from the axis of shaft 2, and thus lie in a circumference described around 20 said shaft, whereby as the strip or band 4 is wound upon them it will assume a circular form, as seen in Fig. 5.

In order to produce circular boxes of various transverse diameters, the plates 5 of the 25 box-side former are made adjustable toward and from shaft 2, and for this purpose I have shown the arms 6 as provided with rack-teeth 6^a, and these arms pass into slots or sockets a b in the inner faces of disks 7 8, that are secured upon shaft 2. The disk 7 is shown provided with a square central opening to receive the squared end 2^a of shaft 2, and the disk 8 is shown provided with a hub 8^a, that has a set-screw 8^b for holding said disk rigidly upon 30 said shaft. Upon shaft 2 between disks 7 and 8 is journaled a rotative sleeve 9, that has annular bosses or flanges 9^a 9^b at its ends, and the outer faces of these disks or bosses are provided with spirally-arranged or worm-like 35 threads 10, that mesh with the rack-teeth 6^a on arms 6. (See Fig. 4^a.) By this means as the sleeve 9 is rotated to the right or left the arms 6 will be moved outwardly or inwardly, as the case may be, in order to increase or decrease 40 the diameter of the box-side former or head. (See Fig. 4.) I have shown the sleeve 9 as provided with capstan-bars 11 for rotating it and with set-screws 12 adapted to hold said sleeve rigidly upon shaft 2 during operations. 45 Upon one of the plates 5 of the box-side former or head is provided means for holding the end of the wooden strip, band, or box side 4, so as to wind the latter upon the former as it rotates. For this purpose I have shown a 50 hook-like plate 13, that is secured to the plate 5 and extends parallel therewith, as shown in Fig. 5. The free edge of this hook is at such a distance from the extending edge of plate 5 as to enable the end of the wooden strip 4 to be passed therebetween, and when the box-side former is rotated the strip 4 will be drawn 55 around by the former in annular shape in the manner shown in Fig. 5. In order to permit the band or wooden strip 5 to be properly presented to the hook 13 and to be held down while being wound upon the box-side former 60 to assist in bending it, I have shown a presser- 65

arm 14, that is provided with a roller 15, adapted to bear upon strip 4, (see Fig. 5,) which presser-arm is shown carried by a lever 16, 70 fulcrumed on a support 17, suitably carried by frame 1. (See Figs. 1, 2, and 5.) The presser-arm 14 is adapted to be raised to permit the passage of strip 4 to hook 13 and then to be depressed so as to bear upon said strip, 75 and for this purpose the lever 16 is to be held firmly in the latter position. To accomplish this, the lever 16 is shown provided with a locking-lever 18, that is pivoted to lever 16, as at 18^a, between the ends of lever 18. The lower end of lever 18 is adapted to rest in steps 19 19^a in a block 20, carried by frame 1, these steps being at different heights, as shown in Fig. 5. A spring 21 connects lever 16 with frame 1, being shown connected 80 to the pivot 18^a and to a hook 22, secured to frame 1. (See Fig. 5.) By this means when the presser-arm 14 is to be applied to band or strip 4 the lower end of lever 18 is set in one of the steps 19 or 19^a and then raised 85 up, said step acting as a fulcrum for said lever, whereupon lever 16 will be tilted to force the presser-arm 14 upon the strip or band 4. It will be understood that the steps 19 19^a are on different planes, so as to provide for box 90 sides of different diameters—that is to say, if the end of lever 18 rests in step 19 the presser-arm 14 can be depressed more than when said lever rests in step 19^a, the latter position of the parts accommodating a box of greater trans- 95 verse diameter than the first-mentioned position.

23 is a rigid arm secured to frame 1 and projecting parallel to presser-arm 14, and upon this arm is a roller 24, upon which the 100 band or strip 4 is adapted to rest, from which it will be understood that the roller 24 acts as a guide for the band or strip 4 to permit its passage under the presser-arm 14 of the box- 105 side former.

By examining Fig. 5 it will be seen that the band or strip 4 when passing to the box-side former will be held and firmly compressed between said former, the presser-arm 14, and the stationary arm 23, whereby as said band 110 or strip is carried around by the box-side former it will be properly bent in a circular direction.

It will be understood that when the strip or band 4 for the box side is wound around the former 5, &c., as shown in Fig. 5, it is to be wound upon a head 25, located at one end thereof, that the box side is to be nailed or tacked longitudinally to join the overlapped portions of the band or strip 4 together, that the surplus material of strip 4 is to be severed, that the box side is to be nailed to the head or bottom 25, and also that a hoop or band may be secured upon the outer side of the box over the portion where the head 25 or bottom is located. For these purposes means are provided for securing the head 25 for the box in the machine in such manner that the strip or band 4 may be wound upon 120 125 130

the same, as shown in Fig. 4. To accomplish this, I provide a disk 26, that is adapted to lie parallel with and to be brought in proximity to the disk 7, so as to clamp the head 25 between said disks, which disk 26 is located concentric to disk 7 when in the operative position. (See Fig. 4.) In order to cause the disk 26 to rotate the box-head 25 and the box-side former, I have shown the disk 26 as provided with pins or studs 26^a and the disk 7 with corresponding pins 7^a, which are adapted to be pressed into the head 25 to firmly unite the disks 26 and 7 rotatively. The disk 26 is adapted to be moved toward and from disk 7 to grip the head 25 between them and to release said head when the box is complete. For this purpose I have shown the disk 26 as secured upon a shaft 27, that in the operative position is concentric with shaft 2 and adapted to be brought in alignment therewith. (See Fig. 4.) The shaft 27 is supported in a suitable bearing 27^a, carried by a gate 28 of suitable construction and hinged to frame 1, so as to be swung across in front of disk 7 and to be moved away therefrom to permit the insertion of head 25 and the removal of the finished box. (See Figs. 1, 2, 3, and 4.) The gate 28 may be suitably hinged to frame 1, and for this purpose I have shown said frame provided with ears 29, which receive a shaft 30, that is journaled in brackets 31, secured to frame 1, and the lower end of said shaft is shown located in a step 32, secured to said frame. The brackets 31 are each provided with two ears 31^a, between which the ears 29 of the gate are located, whereby the gate is held in a firm position. The free end of the gate 28 is shown adapted to rest upon a shelf 33 when it is closed against frame 1, (see Fig. 1,) and suitable means are provided for firmly locking said gate in the closed position. The means I have shown for this purpose consist of a lever 34, pivoted to the gate at 34^a and provided with a shoulder 34^b, that is adapted to ride behind a latch-plate 35, secured to frame 1, said latch-plate being shown provided with a curved edge 35^a to receive the shoulder 34^b, so as to draw the gate tightly shut and hold it in such position. (See Fig. 2.) The shaft 27 is shown provided with a crank-handle 36, by which it can be rotated to cause the head 25 and the box-former to be rotated to wind the box side or strip 4 upon the head 25, the strip 4 being shown so wound upon the head 25 in Fig. 4.

As before explained, the shaft 2 is vertically adjustable, and this is for the purpose of raising and lowering the box-side former relatively to the nailing devices (to be hereinafter described) according to the different diameters of the boxes to be made, and in this connection it is essential that shaft 27 may be likewise adjusted vertically to always have it concentric with shaft 2. For this purpose the bearings 27^a for shaft 27 are shown provided in a suitable box or block

37, carried by the gate 28. The box or block 37 is shown located in a vertical slot 28^a, provided in a panel 28^b in gate 28, and the box 70 37 has vertical grooves on opposite sides that embrace the vertical walls of the slot 28^a of said panel 28^b, as indicated by dotted lines in Fig. 4. By this means the box or block 27 is firmly held in the gate 28 and yet permits proper vertical adjustment, as it will slide in the panel 28^b. I have shown the box or block 37 as resting upon the upper end of a screw 38, that meshes with a threaded bore 38^a in the gate 28, and said screw is shown 80 provided with a hand-wheel 39 for operating it.

40 is a lock nut or wheel threaded on screw 38 and adapted to be set tight against part of the gate to hold the screw in proper position. 85 It will be understood that by adjusting screw 38 up or down the box or block 37 and the shaft 27 will be correspondingly adjusted to bring it into alignment with shaft 2.

The means I have shown for adjusting shaft 90 2 vertically are as follows: The blocks or bearings 3 have side webs or lugs 3^a, that enter vertical slots 41 in brackets or guides 42, that are secured in frame 1, (see Figs. 3 and 4,) and have vertical slots 41^a for the passage of 95 shaft 2. (See Fig. 5.) Upon the shaft 2 are collars 2^a, that are adapted to bear against the bearings or blocks 3 to limit end movement of said shaft. The bearings or blocks 3 are hung upon screws 43, that work in threaded 100 apertures 43^a in webs 44 of the brackets or guides 42. (See Fig. 4.) The lower ends of screws 43 have annular heads 45, that are located beneath reduced portions or necks 45^a, and the heads 45 are located in recesses 3^b in 105 the bearings or blocks 3, and upon these bearings or blocks over the recesses 3^b are secured apertured plates 46, in which are located the necks 45^a of screws 43. The apertures in the plates 46 are smaller than the heads 45 of 110 screws 43, whereby said heads are locked to the bearings or blocks 3 and yet permit the screws 43 to rotate. Upon the upper ends of screws 43 are located sprocket-wheels 47, that are connected by a chain 48, and one of the 115 screws 43 is provided with a hand-wheel 49, whereby it may be rotated.

From the foregoing it will be understood that when the hand-wheel 49 is rotated the screws 43 will be rotated conjointly and at the 120 same speed and that as they rise or descend in their bearings 43^a the bearings or blocks 3 will be likewise raised or lowered, whereby shaft 2 will be correspondingly adjusted up or down.

125 It will be understood that the screws 43 may be connected with the bearings or blocks 3 otherwise than as shown and that the means described for adjusting the bearings or blocks 3 may be altered, if desired. The guides 42 130 are shown connected by braces 50, and these guides have arms 42^a, that extend to and are carried by frame 1, and said guides are also provided with laterally-extending arms 52 at

their lower ends that are secured to frame 1, whereby said guides are securely held in frame 1. The parts 42, 42^a, 50, and 52 thus constitute a small frame within the main frame 1.

5 It will be understood that when the head 25 is to be placed in position between the disks 7 and 26 it should be located concentrically to said disks and that as boxes of different transverse diameters may be made on 10 the machine provision should be made for readily adjusting different-sized heads 25 in position, and, further, that as the diameter of the box at the head gradually increases while the parts of the box are being adjusted together provision should be made for readily 15 permitting of this increase. For these purposes I have shown a guide 53 to receive the head 25 and hold it in position to be clamped between the disks 7 and 26, which guide is shown in the form of a Y and composed of a 20 suitable forging or casting having a depending leg 53^a, that is carried by a lever 54, shown pivoted at 54^a to a bracket 55, secured to frame 1. The leg 53^a is provided with a slot 25 53^b to receive a bolt 56, carried by the upturned end of lever 54, the end of said lever being preferably provided with an offset to receive the leg 53^a to keep the same in vertical position. The upper arms of guide 53 30 are shown twisted or bent at an angle to the leg 53^a, (see Figs. 2 and 4,) so that they present a flat surface to the head 25, and the guide 53 is located in line with the space between the disks 7 and 26 and in such position that 35 the head 25 may rest in the arms of said guide and be thus held in position to be clamped between the disks 7 and 26. (See Fig. 4.) When the heads 25 of different-sized boxes are to be used, the guide 53 can be adjusted 40 vertically, so as to always bring the heads in the proper position concentric to shaft 2. The free end of lever 54 is shown provided with an adjustable counterweight 57, adapted to balance the weight of the parts and the head 25 when upon guide 53, and said lever is shown located in a slot 58^a in a guide 58, 45 secured to frame 1, whereby the free end of lever 54 may have a limited vertical movement.

50 59 is an adjusting-screw threaded in an aperture in guide 58 and adapted to limit the downward movement of lever 54. By this means as the diameter around the periphery of head 25 increases as the box is being produced the lever 54 can tilt, while the box acts upon guide 53 to depress the same. Furthermore, by means of the two adjustments 56 and 59 the box-head 25 can always be accurately adjusted concentric to shaft 2, according 55 to the size of the box to be produced.

Having explained how the box may be formed and applied to its head 25, I will now describe the means I have shown for nailing the overlapped portions of the box side together and for nailing the box to the head 5 around the latter and also for applying a 60 hoop around the box over the head.

I will first describe the device for nailing the overlapped portions of the box side or strip 4 together. For this purpose I have 70 shown a nailing-head 60, which is located on a plane above the box-side former carried by shaft 2, and it is adapted to travel longitudinally over the wound strip 4. The main part of the nailing-head 60 comprises an angle-plate or support 61, having a vertical portion 61^a, a horizontal portion 61^b, and a strengthening rib or web 61^c, (see Fig. 7,) and the same is secured upon a plate 62, that extends from a bracket 63, which has arms 63^a, that are secured to shafts 64, supported in bearings 65, carried by the arms 42^a of brackets 42, (see Figs. 2 and 3,) said shafts 64 being adapted to slide longitudinally to enable the nailing-head to have the same movement over the box 85 side 4 upon former 5, &c. At the front face of the vertical web 61^a are two plates 66, that extend at right angles to said web and project outwardly therefrom and bear against the front face thereof, (see Fig. 8,) which plates 90 are connected at their lower portion by a block 67, secured to them, Fig. 7. At their lower ends the plates 66 have angle-plates 68 secured to them, the inwardly-bent ends 68^a of which extend into vertical recesses 68^b in 95 the wall of the web 61^b and also take behind the upright 61^a to guide the plates 66. (See Fig. 8.) At the upper end of web 61^a are secured angle-plates 69, whose bent forward ends 69^a overlap the front vertical edges of 100 the plates 66, so as to guide the latter, the parts 68 and 69 thus permitting the plates 66 to have vertical movement on upright 61^a. The plates 66 near their upper ends have vertically-arranged slots 66^a, in which are located 105 webs 70^a, that extend from the ends of a block 70, which is located between the plates 66, and is thus guided to have vertical movement independent of plates 66. The block 70 carries a plunger 71, that is adapted to force 110 nails or tacks through the lapped portions of the band or box side 4 to secure them together. For this purpose the block 70 is shown provided with an offset 70^b, that has a recess or bore 70^c in its undersurface, in which 115 the plunger 71 fits, the bottom of said recess serving as an abutment for said plunger, and the offset 70^b is provided with a threaded aperture 70^d, passing into one side and meeting the recess 70^c, in which aperture 70^d is located 120 a set-screw 72, that is adapted to impinge upon plunger 71 to hold it securely in position in offset 70^b. (See Fig. 6.) The offset 70^b is to be connected by one or more links 73 with means for reciprocating the block 70. I have shown two links 73, that are journaled 125 on a pin 74, carried by ears 74^a, that project from the offset 70^b of block 70, there being two links 73 and three of such ears 74^a, between which said links are located. (See 130 Figs. 6 and 7.) The upper ends of links 73 are shown pivotally connected with a rocker-arm 75, that projects from a rock-shaft 76, that will be more fully described hereinafter.

The lower end of plunger 71 works in a bore 77^a in a nail-box 77 (constituting part of feeder-head 60) and is adapted to push nails therefrom and to drive them into the box side.

5 The nail-box 77 is also provided with a bore 77^b, to which a tube 78 leads from a nail-supply, to be hereinafter described. The details of construction of this nail-box 77 are shown more clearly in Figs. 6 and 7, wherein the box 10 77 is shown composed of two castings 77^c, placed side by side and each provided with half of the bores 77^a 77^b, said castings being suitably secured together. Each casting 77^c of the box 77 has an extension 79, that projects inwardly and rests upon the block 67 and may be secured thereto in suitable manner. I have shown the block 67 as provided with a screw 80, that passes through or between the extensions 79, and at its upper end 15 20 it is provided with a capstan-nut 81 for holding said extensions upon block 67. The block 67 is provided with a square recess 67^a, in which the head of nut 80 is located, which recess opens through the front wall of said block, 25 and said recess is extended vertically above said nut, but of less area, to receive the threaded part of screw 80, so that the screw will not pull upwardly, and in front of the recess 67^a is secured a plate 82, that is shown 30 held to block 67 by screws 82^a, whereby the head of screw 80 is held in block 67 and kept from rotating therein. The nail-box 77 is provided with two downwardly-extending pivoted jaws 83 84, that are located in suitable 35 recesses 83^a 84^a in said box and hung upon pivots 83^b 84^b carried thereby. (See Fig. 7.) The jaws 83 84 are beneath the bores 77^a 77^b of box 77 and are adapted to receive the nails from bore 77^b and to permit the passage between them of said nails and of the plunger 71. 40 The jaws 83 84 abut in their normal positions, and on their meeting faces they are provided with a corresponding groove or recess 83^c 84^c, forming a bore adapted to receive a nail or 45 tack 91 between them, as shown in dotted lines in Fig. 7. The lower ends of these recesses 83^c 84^c taper toward each other, so that the vertical edges 85 of said jaws may abut to prevent the spontaneous passage of the nail 50 55 from between said jaws. At the upper ends of the recesses 83^c 84^c the jaws 83 84 are beveled inwardly and downwardly, forming shoulders at 85^a 85^b to receive the lower end of plunger 71; whereby as said plunger is forced against said shoulders it will spread the jaws 83 84 apart to permit the passage of the nail from between them, so that said nail may be driven into the box side. The jaws 83 84 are normally held closed by means of 60 65 springs 86 87, that are shown coiled around pins 88 89, carried by the box 77, the ends of said springs bearing against the jaws 83 84. (See Fig. 7.)

It will be understood that the block 70 is to be reciprocated by crank-arm 75 in order to operate the plunger 71 and that the webs 70^a travel in the slots 66^a of plates 66 and push

the latter downwardly. To give a slight vertical movement to the nail-box 77 to normally hold it out of contact with the box side, 70 I provide springs 90, which are shown connected to the plate 82 and to the upright 61^a, whereby the springs normally hold plate 82 in contact with stops 82^b, carried by upright 61^a. The depth of slots 66^a is slightly shorter than 75 the full downstroke of block 70, and as the plunger descends it drives the nail into the wood clear of the bottom of the nail-box, and then the webs 70^a encounter the bottoms of the slots, and the plates 66 are then pushed 80 down, thereby carrying the nail-box down upon the work as the plunger continues to descend, and the nail-box presses the lapped parts of the wood together, the plunger meanwhile completing the nailing operation. On 85 the return or up stroke of block 70 the springs 90 pull the plate 82 and the nail-box upwardly from the box side until arrested by the stops 82^b, and thus the box side is free to rotate under the nail-box after the nail has been 90 driven.

In order to clinch the nails 91 that are driven into the overlapped portions of the box side by the plunger 71, I provide an anvil or plate 92, that is carried by one of the plates 95 5 of the box-side former, and this anvil or plate 92 is shown located in a recess in the outer surface of said plate 5, (see Fig. 5,) and it may be secured in place by screws or rivets 93. (See Fig. 4.) Thus it will be seen 100 that the anvil 92 is secured to the same plate 5 of the box-side former as the hook 13, and when the box side or band 4 is wound upon the box-side former, so that its end portions overlap, the plate 5, that carries the anvil 92, 105 will be brought to rest under the nail-box 77, so that as the nails are driven through the overlapped portions of the box side they will impinge against the anvil and will thus be clinched against the inner side of the box. 110 (See Fig. 5.)

It will be understood that as the nails are being driven into the box side the complete nailing-head 60, carried by the shaft 64, will be fed forwardly over the box side by a step-by-step movement, and for this purpose I have shown an arrangement as follows: 94 is a lever or crank handle secured to shaft 76 for rocking the same, and 95 is a crank-arm also secured to shaft 76, and to this crank-arm is pivoted a dog or pawl 96, that is adapted to engage a rack 97, suitably secured upon frame 1. (See Figs. 2 and 3.) I have shown the rack 97 in the form of a rack-bar, having bolts 97^a, that secure it upon frame 1. 125

From the foregoing it will be understood that when lever or crank handle 94 is moved in the direction of the arrow α in Fig. 2 it will rock the shaft 76, whereupon crank-arm 95 will be moved forward and draw dog or pawl 130 96 over one tooth of rack 97, while the crank-arm 75 is being operated to depress plunger 71 to drive a nail, that after the nail is driven the lever or crank 94 will be moved in the re-

verse direction to raise plunger 71, while at the same time dog 96 will abut against the contiguous tooth of rack 97 and crank-arm 95, finding a fulcrum at 96^a, will cause shaft 76 to travel forwardly, whereupon bracket 63, shafts 64, and the nail-feeding devices will be caused to move forwardly over the box-side former one step equal to the length of a tooth of rack 97. Thus each time that lever 10 or crank arm 94 is swung forwardly and back a nail will be driven into the box side and the nailing devices will be moved one step in position to apply a new nail.

In order to permit the shaft 64 and the attached nailing devices to be moved backwardly to their normal positions after having driven a row of nails throughout the length of the side of the box, the dog 96 is to be disengaged from the rack 97, so as to permit the 20 nailing devices to be moved back to their normal position, as shown in Fig. 2. For this purpose I have shown a device that will automatically cause the dog 96 to be disengaged from rack 97 as the last nail is being driven 25 into the box side. The arrangement for this purpose is as follows: At one side of rack 97 is located a plate 98, that is adapted to slide longitudinally, and it is shown held to the rack-bar 97 by pins or bolts 99, that pass 30 through slots 98^a in plate 98. These slots are inclined in an upward and forward direction, so that when plate 98 is moved to the right in Fig. 2 it will rise to cause its upper edge to pass slightly above the plane of the rack-teeth 97, and when moved to the left in Fig. 35 2 said upper edge will pass to a plane about level with the bottom of said rack-teeth in the position shown in said figure. When the plate 98 is drawn forwardly, so that its edge 40 shall be above the rack-teeth 97, it will be in position to engage a lip 96^b, (see Fig. 2,) that projects laterally from the operative end of dog 96, whereupon said dog will be lifted out of said rack-teeth, so that the dog may slide 45 upon the edge of plate 98 rearwardly without engaging the rack-teeth. The plate 98 is shown provided with an upwardly-extending finger 100, that is adapted to be engaged by the lip 96^b, and the finger 100 is located adjacent to the last or forward tooth of rack 97, so that when the nail-feeding devices have 50 moved forward in position to drive the last nail in the box side near the bottom thereof and the lever or crank handle 94 is moved 55 forwardly to drive the last nail the lip 96^b will engage the finger 100 and draw the plate 98 forwardly, whereupon the upper edge of said plate will pass above the rack-teeth 97, and said lip will rest upon said plate. Now 60 when the nailing devices are pushed rearwardly the lip 96^b will cause the dog 96 to slip over the rack-teeth 97, and it is designed that the dog 96 will cause the plate 98 to be pushed back to its normal position, as shown 65 in Fig. 2. For this purpose a pin 101 is placed in an aperture in the upper edge of plate 98 and in position to be engaged by lip 96^b of dog

96. Thus when lip 96^b reaches the pin 101 it will push said pin and the plate 98 rearwardly to depress the top edge of said plate, so as to 70 permit the dog 96 to engage the rack 97. By preference the upper edge of plate 98 is provided with a series of holes to receive pin 101, so that the latter may be adjusted along the plate 98, by which means the amount of rearward movement of the nailing devices can be limited to regulate the point at which the first nail shall be driven into a box side in accordance with the height of the various boxes to be made, because when the dog 96 pushes pin 80 101 and plate 98 backwardly it will engage one of the teeth of said rack 97, and thus determine how far back the nailing devices can be pushed for different-sized boxes.

It is designed that as the nailing-head 60 is 85 moved forwardly step by step over the box side the surplus material A of the band or strip 4 shall be severed, and for this purpose I provide a knife B, that is connected rigidly to the plate 62 and has its cutting edge b extended downwardly and rearwardly, as clearly shown in Fig. 7. By preference the knife or blade B has two of such cutting edges b b'. The knife B is detachably connected with the plate 62, and for this purpose it is shown lying in a groove or recess in an extension C², that rises from a bar C, that extends under plate 62 and may be secured thereto by screws C³. (See Figs. 6, 7, and 7^a.) The knife B is held to the extension C² by the screw D, that passes through a slot d in said extension and meshes with a tapped hole in the knife B. (See Figs. 2 and 6.) The knife B may have a plurality of tapped holes for the screw D to permit vertical adjustment. It will be seen 95 that the knife or blade B extends below the nail-box 77, so as to come in contact with the strip or band 4. (See Fig. 5.) Thus as the nail-box 77 is moved forwardly to drive the 100 nails the knife or blade B will cut through and sever the strip or band 4, so that when the box side is completely nailed the surplus material thereof will be separated therefrom.

It will be understood that as each nail is 115 driven into the box side a new nail will be passed forward into the nail-box 77, and for this purpose I have shown arrangements which may be described as follows: To the bracket 63 is secured a standard 102, from which projects a bracket 103, to which the nail selecting or separating devices are attached, and 104 is an angle-arm, also secured to standard 102, from the depending arm of which projects a bracket 105, to which a funnel 106 is secured, which funnel connects 120 with the tube 78, that leads to the nail-box 77. From the upright 61^a extends an arm 78^a, that is connected with tube 78 to assist in holding the latter. The arm 103 is shown adjustable toward and from the standard 102 by 125 means of a screw 104^a, that passes through a slot 104^b in the horizontal web of arm 104, which screw is threaded into the bracket 103. (See Fig. 14.) The bracket 105 is shown as 130

adjustable vertically with relation to arm 104 by means of a slot 105^a in the depending arm of said bracket, through which a screw 105^b passes and is threaded into the depending web of arm 104. (See Fig. 14.) The bracket 105 at its outer end is provided with a clamp 107, adapted to engage and hold the funnel 106, whereby funnels of different sizes may be used according to the various-sized nails. 5 The upper flaring end of funnel 106 is located beneath the nail selecting or distributing device that is adapted to feed nails one by one to said funnel. The device I have shown for this purpose is organized as follows: The bracket 103 is shown provided with arms 103^a 103^b, having a suitable space between them, in which arms are journaled a frame 107, the arm 107^a of frame 107 being shown hung upon a rock-shaft 108, that is journaled in 10 bearings on arm 103^a, the other arm 107^b of frame 107 being connected with arm 103^b by a pivot 109. (See Fig. 11.) The opposite end of frame 107 is shown supported by a link 110, that is pivoted at 111 to a projection 112 15 on bracket 103, and the link 110 is provided with a slot 110^a, that receives a screw 113, carried by frame 107, whereby the link 110 may be secured to said frame, and the latter may be adjusted vertically by means of screw 113 and slot 110^a to alter the inclination of 20 said frame. (See Figs. 2, 3, 10, and 11.) To the under side of frame 107 is secured a track or chute 114, having a longitudinal slot 115, through which the nails 91 may project and 25 down which track or chute they may slide to the funnel 106. At the lower end of track 114, directly above funnel 106, the nail-selecting devices are located. These devices consist of two parallel longitudinally-movable 30 rods 116 117, that are carried in bearings at the outer ends of the arms 107^a 107^b of frame 107. The rods 116 117 at one end have pins 116^a 117^a, between which and the arms 107^a are located springs 118 119, that are coiled 35 upon said rods and serve to hold the ends of the latter against a cam 120, that is secured upon rock-shaft 108. The cam 120 is shown generally in the form of a sector having suitably-shaped cam-faces 120^a 120^b, that are 40 adapted to engage the ends of rods 116 117, respectively, (see Figs. 13 and 14,) whereby as the cam 120 is rocked it will, in conjunction with springs 118 119, move the rods 116 117 back and forth longitudinally. The rock-shaft 108 has a crank-arm 108^a, that is pivotally connected by a link 121 with a crank-arm 122, to which said link is pivoted. The 45 crank-arm 122 is shown provided with a plurality of holes to receive the pivot 121^a to provide different adjustments for link 121. The crank-arm 122 is secured to rock-shaft 76, so that as the latter is rocked to reciprocate the plunger 71 the cam 120 will be operated to select and feed the nails 91 one by one. From 50 the rod 116 depends a finger 123, that is adapted to pass across the end of slot 115 in track

or chute 114 to arrest the passage of nails 91. By preference the finger 123 is pivoted to rod 116 at 123^a, and said finger is shown provided with an extension 123^b, which receives a spring 70 124, interposed between said extension and the rod 116, and the finger 123 also has a lip 123^c to engage rod 116, the action of which parts is to hold finger 123 in the normal position, and yet to permit it to move to the left 75 in Fig. 13 if the lower operative end of said finger meets with an obstruction—as, for instance, a nail that does not properly pass from slot 115. Rod 117 carries a nail-selecting pin 125, that is shown adapted to pass at right 80 angles to slot 115 of track or chute 114, so as to obstruct the passage of nails 91. The pin 125 is shown carried by a finger 126, that is connected with rod 117, and said finger is shown pivoted to said rod by a pivot 126^a, that 85 enters the latter, and the finger 126 is shown provided with an extension 126^b. A spring 127 is interposed between extension 126^b and rod 117, and the finger 126 has a lip 126^c, that engages rod 117. By this means finger 126 is held in the normal position and is permitted to tilt to the right in Fig. 13 if the pin 125 meets with an obstruction, such as a nail 91, that has not properly passed from track or chute 114. The operation of 90 the nail-feeding devices is substantially similar to that of the nail-feeding devices of Patent No. 461,013, issued to me on October 13, 1891.

The nails 91 are fed to the track or chute 100 114 from a rocking nail-pan 128. The pan 128 may be of suitable or usual construction, and in its bottom it has a slot 128^a, through which the nails 91 may pass and hang by their heads in the usual manner, which slot 105 leads through the front wall 128^b, at its lower edge, and the lower end of the slot 128^a is connected with fingers 129, that project from the outer end of the box and overlie the track or chute 114, having a space 129^a between 110 them for the passage of the nails from slot 128^a to said track or chute.

130 is a horizontal gate at the lower end of pan 128, arranged in the usual manner. The pan 128 is pivotally connected with frame 107, 115 and in order to permit said pan to be readily disconnected from said frame I have shown the lower end of the pan 128 as provided with outwardly-extending arms 131, that have gudgeons or pivots 132, that are journaled in 120 sockets 133^a, located in ears 133 of frame 107. (See Figs. 10 and 12.) By this means the pan 128 can be readily lifted from frame 107, and yet can rock upon the parts 132 133. In order to hold the lower end of pan 128 down, so 125 as to retain the gudgeons 132 in sockets 133^a, I have shown a spring 134, that connects with frame 107 or ears 133 and also with pan 128, said spring being under tension to draw the lower end of pan 128 downwardly. The 130 spring 134 may be connected with pan 128 or with ear 133, or both, by a hook or hooks 135,

carried by one or both of said parts, whereby the spring 134 can be detached when it is desired to remove pan 128.

The means I have shown for rocking pan 128 are as follows: To the outer end of pan 128 is pivotally connected a link 136, that is pivotally connected with a rocking lever or working beam 137, which is pivoted between its ends, as at 137^a, to uprights 138, that are connected with shafts 64. I have shown a pair of uprights 138, (see Fig. 1,) and the lower ends of these uprights are shown connected with socket-pieces 139, secured upon shafts 64, so that as the shafts 64 reciprocate the uprights 138 will follow. The pivots 137^a (or the uprights 138) are connected by braces 140 with standard 102, there being two of such braces 140, (see Fig. 1,) whereby the pivot 137^a is firmly held, and as standard 102 is connected with shafts 64 through the medium of brackets 63 the parts 64, 63, 102, 140, 137^a, 138, and 139 are united in a firm structure, so that all reciprocate with the nail-feeding devices. The outer end of lever or working beam 137 is pivotally connected with a link 141, which at its lower end is pivoted to bar 142, the opposite end of which is rigidly connected with crank-arm 95. From this it will be understood that when shaft 76 is rocked a rocking motion will be transmitted to lever or working beam 137, and thus the pan 128 will be worked up and down for the purpose of shifting the nails about to cause them to pass through the slot 128^a in the bottom thereof.

Having thus far described the device for nailing the overlapped portions of the box side together, it remains to be explained how the box side is nailed to the head 25 and the hoop applied around the same. The nailing devices for the head of the box are carried by the gate 28, and these nailing devices, particularly the nail-box 77 and the nail-distributing devices, are substantially the same as those heretofore described, and they will therefore need no further particular description, and wherever the nailing devices carried by the gate correspond with those previously described I will apply the same reference-letters thereto, so that the description of one set will suffice for both. There are, however, some changes in connection with these nailing devices, particularly in the manner of operating the same, and these will be described more at length. To the gate 28 is secured an upright 61^a, to which a nail-box 77 and its associate parts are connected, such as previously described. The nail-delivery end of the nail-box 77 is located directly over the head 25 when the gate 28 is closed, as shown in Fig. 4, and in this case there is no knife B connected with said feeder. The link 73, that connects with the plunger 71, is in this case connected with a lever 150, that is shown pivoted to an arm 152, that projects from the upright 61^a, (see Fig. 1,) whereby as said lever is rocked the plunger 71 will be

reciprocated to drive nails through the box side into the head 25. To the lever 150 is also pivotally connected a link 121, that operates the arm 108^a of shaft 108, that carries cam 120 for operating the nail-selecting devices, so that as the lever 150 is rocked cam 120 will be operated to act in selecting nails for the box-head. Lever 150 is also connected with the rocking nail-pan 128 by a link 153, pivoted to said lever at 153^a, the lever 150 and the link 153 being shown provided with a plurality of apertures to permit adjustment of pivot 153^a to give pan 128 more or less movement. Thus when lever 150 is depressed to cause plunger 71 to drive a nail the pan 128 will be lifted, and vice versa. It is designed that as each nail is driven into the box-head the latter will be rotated step by step a suitable distance, and for this purpose I have provided connections between the lever 150 and shaft 27 for so rotating the box-head. Upon shaft 27 is secured a ratchet-wheel 154, and upon said shaft is journaled an arm 155, to which is pivoted a dog 156, that is adapted to engage the teeth of ratchet-wheel 154. (See Fig. 1.) From arm 155, and preferably connected with the pivot 157, by which dog 156 is connected to said arm, extends a rod 158, that is pivotally connected with lever 150, as by a pin 159, carried thereby. A spring 160, connected with arm 155 and with dog 156, serves to normally hold said dog in engagement with the ratchet-wheel 154. Thus when lever 150 is depressed by the operator the plunger 71, connected therewith, will drive a nail into the box-head through the box side, and when said lever is raised the rod 158 will be depressed, thereby carrying down arm 155 and dog 156, thus rotating shaft 27 and box-head 25 one step. By preference the rod 158 is provided with a plurality of holes 158^a, by which pivot 157 can be adjusted along said rod to cause dog 156 to assume different positions relatively to ratchet-wheel 154. I have shown an arrangement whereby the dog 156 is under the control of the operator. For this purpose the outer end of said dog is shown pivotally connected by a rod 161 with one arm of a bell-crank lever 162, pivotally connected with lever 150, as by the pivot 159, and the other arm of said bell-crank lever is connected by a rod 163 with a bell-crank 164, that is pivotally connected with lever 150, as by a pivot 165, the lever 164 having an arm 166, adapted to be grasped by the hand of the operator. (See Fig. 1.) Thus when the arm 166 is drawn toward lever 150 bell-crank lever 162 will be tilted and will draw on rod 161 to disengage dog 156 from ratchet-wheel 154. By this means lever 150 can be operated independently without rotating shaft 127 and the box-head connected therewith. I have shown the rod 161 as provided with a plurality of holes 161^a, adapted to receive the pivot 161^b, that connects rod 161 with dog 156 to permit adjustment between said rod and said dog.

It will be understood that when lever 150 is depressed the nail-box 77, carried by the gate 28, will drop down upon the box over the head 25 in manner similar to that described with regard to the nail-box 77, that is carried by shafts 64, and that when lever 150 is raised the said nail-box 77 will be lifted from said box through the influence of plates 66 and block 70 in manner before described. When it is desired to apply a hoop or band 167 around the bottom of the box and over the head 25, (see Fig. 4,) said band is fed into the machine directly beneath the nail-box 77, that is carried by gate 28, and as the nails are driven by said feeder they will pass through said hoop, through the box side, and into the head 25, thus securing said parts together. As the head 25 and the box are given a step-by-step rotary motion through the medium of lever 150, ratchet-wheel 154, and the connected parts, the hoop 167 will be gradually fed into the machine and nailed as it is fed. In order to properly guide the hoop 167 over the head 25, I have shown the gate 28 as provided with a guide 168, that has a vertical web 168^a, that is located adjacent to the head 25 and parallel therewith when the gate 28 is closed, against which web the hoop 167 may bear. (See Figs. 4 and 4^b.) The guide 168 is shown secured to gate 28 by bolts 169, and in order that said guide will not interfere with the nailing devices 77, carried by shafts 64, when they have reached the bottom of the box said guide is shown provided with a depression 168^b. Thus the guide 168 is shown in the form of a hook having its operative part extending from the inner face of gate 28, and its part 168^a extends forwardly tangentially of head 25 in position to be engaged by the band 4. As shown in Fig. 1, the nailing devices 77, &c., that are carried by gate 28, are located a little to one side of the plane of the nailing devices 77, &c., carried by shafts 64, and the guide 168 is located a little to the left (Fig. 1) of the nailing devices 77, carried by shafts 64; but the upper edge of web 168^a of guide 168 alines with or projects slightly above the periphery of the box. The standard 102, that is carried by gate 28 for the nail-selecting devices, is shown somewhat in different form from that previously described; but that is immaterial.

The complete operation of the machine in making a box is as follows: The gate 28 is opened. The box-side former 5, 6, &c., is adjusted to the size of the box to be made. Shafts 2 and 27 are adjusted correspondingly, and the guide 53 is adjusted vertically, so as to hold the proper-sized head 25 in position concentric with the shaft 2. A head 25 is next placed upon guide 53, so as to abut against the plates 5 of the box-side former, and the gate is then closed and locked, whereupon the teeth 7^a 26^a will be pressed into the head 25, and thus the parts 2, 7, 25, and 27 will be rotatively united together. The band or strip 4 for the box side is then passed between rollers 15 and 24 until its end engages hook 13, carried by plate 5, the levers 16 18 having been first operated so as to raise roller 15. The roller 15 is then pressed down upon strip 4 by placing the end of lever 18 in step 19 or 19^a and raising the free end of the same, causing lever 16 to carry roller 15 down upon band 4. The crank or handle 36 is then rotated, whereupon head 25 and the box-side former 5, &c., will be carried around, and the band 4 will be wound around the box-side former and the head 5 until it overlaps, as shown in Fig. 5, whereupon the parts will be brought to rest, with the anvil 92 beneath the nail-box 77, that is carried by shafts 64. Said nail-box 77 will have been adjusted to its rearward position, so that the first nail to be driven in the box side will be near the edge of the latter opposite the head 25. Lever 94 will be next moved in the direction of the arrow x in Fig. 2 to drive a nail through the overlapped portions of the box side, whereupon dog 97 will step forward across one tooth of rack-bar 96, and the pan 128 through its connections with shaft 76 will be tilted on its pivot and the cam 120 will be rocked to cause the parts it controls to select a nail. Lever 94 is next moved backwardly, whereupon the plunger 71 is raised, cam 120 is operated to cause a new nail to drop to nail-box 77, crank-arm 95 is moved back to cause pan 128 to operate, and dog 96 by abutting against a tooth of rack 97 causes the nail-box 77, shafts 64, and the connected parts to move forwardly one step. This process is repeated each time lever 94 is rocked forth and back, and the nails are thus driven into the sides of the box at suitable distances apart step by step until the said nail-box 77 reaches the lower end of the box and the last nail is driven into the side thereof. During the stroke that drives the last nail the lip 96^b of dog 96 engages finger 100, and thus draws plate 98, which rises and acts to release the dog from the rack-teeth. During the time that the nail-box 77 is being moved along to drive the nails the knife B will be acting to cut the surplus material from the strip or band 4, as previously described. Thereupon the sides of the box are to be nailed to the bottom 25, and if a hoop 157 is to be fastened to the box the latter is fed under the box 77, carried by gate 28. Whether the hoop is there or not the feeding of the box side to the head will be accomplished as follows: Lever 150 is first depressed, whereupon the plunger 71, connected therewith, will be forced down to drive a nail through the box side (and hoop) and into the head 25, while at the same time rod 158 will lift arm 155 and dog 156, and lever 150 will raise pan 128 and will also cause cam 120 to operate the nail-selecting devices controlled thereby. Lever 150 will next be raised, whereupon the plunger 71 will rise, pan 128 will be depressed, cam 120 will cause a new nail to drop to the box 77, and as the outer end of lever 150 descends it will cause

dog 156 to rotate ratchet-wheel 154, shaft 27, and the box head and sides one step. This is continued each time lever 150 is operated, thus rotating the box-head and the box side 5 intermittently step by step and driving a nail each time a new portion of the box side and head is moved beneath the box 77. When the sides of the box are thus nailed to the head 25, the gate 28 is swung open and the box removed from the machine complete and ready for use.

I do not limit my invention to the precise details of construction shown and described, as they may be varied without departing from 15 the spirit thereof.

Having now described my invention, what I claim is—

1. A box-making machine comprising a frame, a box-side former rotatively carried thereby, a gate connected with said frame, means carried by said gate for clamping a box-head to said former, and for rotating said head and former, and means for driving nails into the box side and for nailing the box to 20 said head, substantially as described.

2. A box-making machine comprising a frame, a box-side former rotatively carried thereby, a gate connected with said frame, means carried by said gate for clamping a box-head to said former, means carried by 30 the gate for rotating said head and former, means for driving nails into the box side and for nailing the box to said head, and means for cutting off the surplus material of the box side as the same is being nailed, substantially as described.

3. A box-making machine comprising a frame, a box-side former rotatively carried thereby, a gate pivotally connected with said frame, a shaft rotatively carried by said gate, a clamping device carried by said shaft to 40 clamp a box-head to said former, means for rotating said clamping device to rotate the box head and former, and means for nailing the box side together and the box side to said head, substantially as described.

4. A box-making machine comprising a frame, a box-side former rotatively carried thereby and having a clamping-disk, a gate 50 pivotally connected with said frame, a shaft rotatively carried by said gate, a clamping-disk carried by said shaft for rotatively connecting a box-head with the disk of the box-side former, means for rotating said shaft to 55 rotate said head and said former, and means for nailing the overlapped portions of the box side together and the box side to said head, substantially as described.

5. A box-making machine comprising a frame, a box-side former rotatively carried thereby and having a disk provided with 60 projections or pins, a gate pivotally connected with said frame, a shaft rotatively carried by said gate, a disk carried by said shaft and having projections or pins and adapted to 65 clamp a box-head to the disk of the box-side former, means for rotating said shaft to ro-

tate said disks and head, and means for nailing the overlapped portions of the box side and the box side to said head, substantially 70 as described.

6. A box-making machine comprising a frame, a box-side former rotatively carried thereby, a gate pivotally connected with said frame, means for clamping a box-head to 75 said box-side former, a guide located beneath said former between the frame and the gate and adapted to hold the box-head in position against the former, and means for nailing the overlapped portions of the box side and box 80 side to said head, substantially as described.

7. A box-making machine comprising a frame, a box-side former rotatively carried thereby, a gate pivotally connected with said frame, means for clamping a box-head to 85 said former, means for rotating said head and former, a forked guide located beneath said former between the frame and the gate and movably supported to have vertical movement to hold a head in position to be clamped 90 to said former, means for movably supporting said guide, and means for nailing the overlapped portions of the box side and the box side to said head, substantially as described.

8. A box-making machine comprising a 95 frame, a box-side former rotatively carried thereby, a gate pivotally carried by said frame, means carried by the gate for clamping a box-head to said former, a forked guide located beneath the former between the frame and 100 the gate and adapted to hold the head in position to be clamped to said former, a lever pivotally carried by said frame to which said guide is connected to allow the guide to move toward and from the former, and means for 105 nailing the overlapped portions of the box side and the box side to said head, substantially as described.

9. A box-making machine comprising a frame, a box-side former rotatively carried 110 thereby, a gate pivotally carried by said frame, means carried by the gate for clamping a box-head to said former, a forked guide located beneath the former between the frame and the gate and adapted to hold a head in position 115 to be clamped to said former, a lever pivotally carried by said frame and having a counterweight to allow the guide to move toward and from the former, said guide being adjustably carried by said lever, and means for 120 nailing the overlapped portions of the box side together and the box side to said head, substantially as described.

10. A box-making machine comprising a frame, a box-side former rotatively carried 125 thereby, a gate pivotally carried by said frame, means carried by the gate for clamping a box-head to said former, a forked guide located beneath the former between the frame and the gate and adapted to hold a head in position 130 to be clamped to said former, a lever pivotally carried by said frame to allow the guide to move toward and from the former, a counterweight carried by the lever, said guide be-

ing adjustably connected with said lever, means for regulating the position of the free end of said lever, and means for nailing the overlapped portions of the box side together, 5 and the box side to said head, substantially as described.

11. A box-making machine comprising a frame, a box-side former rotatively carried thereby, a gate pivotally carried by said frame, 10 means carried by the gate for clamping a box-head to said former, a forked guide located beneath said former between the frame and the gate and adapted to hold a head in position to be clamped to said former, a lever pivotally carried by said frame to allow the guide to move toward and from the former, a counterweight carried by said lever, said guide having two upwardly-projecting arms and a depending arm adjustably connected with 20 said lever, means for regulating the movement of the outer end of said lever, and means for nailing the overlapped portions of the box together and the box side to said head, substantially as described.

12. A box-making machine comprising a frame, a horizontal shaft carried thereby, a box-side former carried by said shaft and comprising means for increasing and decreasing its diameter, said shaft being adjustably held 30 to enable its location to be altered, means adjustably carried by said frame for clamping a box-head to said former, whereby said means may be alined with said shaft in the different positions of the latter, means for rotating said 35 box-head when clamped to said box-side former, and means for nailing the overlapped portions of the side together and the box side to said head, substantially as described.

13. A box-making machine comprising a frame, a shaft adjustably carried thereby so 40 that its position may be altered, a box-side former carried by said shaft and comprising means for increasing and decreasing its diameter, a shaft adjustably carried by said frame to enable it to be alined with the first-mentioned shaft in any position of the latter, means carried by the second-mentioned shaft for clamping a box-head to the box-side former, and means for nailing the overlapped 45 portions of the box side together and the box side to said head, substantially as described.

14. A box-making machine comprising a frame, a shaft extending longitudinally thereof, bearings for said shaft, means for supporting and adjusting said bearings vertically in said frame, a box-side former carried by said shaft, said former comprising means for increasing and decreasing its diameter, a gate pivotally carried by said frame, a shaft 27, a bearing for said shaft adjustably carried by said gate, means carried by said shaft for clamping a box-head to the box-side former, means for operating said shafts, and means for nailing the overlapped portions of the box 60 together and the box side to said head, substantially as described.

15. A box-making machine comprising a

frame, a shaft extending longitudinally thereof, bearings for said shaft, screws rotatively connected with said bearings and arranged to support the same, means carried by said frame for supporting said screws to cause them to be raised or lowered as they are rotated, means for rotating said screws in conjunction, a box-side former carried by said shaft and comprising means for increasing and decreasing its diameter, a gate pivotally connected with said frame, a shaft 27, a bearing for said shaft adjustably carried by said gate, a screw for operating said bearing, 80 means carried by the shaft 27 for clamping a box-head to the box-side former, and means for nailing the overlapped portions of the box side together and the box side to said head, substantially as described. 85

16. The combination of a frame, a shaft located longitudinally thereof, bearings for said shaft, screws rotatively connected with said bearings and arranged to support the latter, supports for said screws having threaded bores with which said screws mesh, sprocket-wheels carried by said screws, a chain connecting said sprocket-wheels, means for rotating one of said screws to communicate motion to the other, a box-side former carried by 95 said shaft and comprising means for increasing and decreasing its diameter, means for clamping a box-head to said former, means for rotating said head and former, and means for nailing the overlapped portions of the box 100 side together and the box side to said head, substantially as described.

17. A box-making machine comprising a frame, a shaft located longitudinally thereof, bearings for said shaft, means for adjustably supporting said bearings so as to raise and lower said shaft, a gate pivotally connected with said frame, a shaft 27, a bearing for said shaft carried in guides in said gate, said gate having a threaded aperture 38^a, a screw meshing in said aperture whereby said bearing can be adjusted, means carried by shaft 27 for clamping a box-head to the box-side former, means for rotating said head and box-side former, and means for nailing the overlapped 110 portions of the box side together and the box side to said head, substantially as described. 115

18. A box-making machine comprising a frame, a shaft rotatively carried thereby, means for adjusting the shaft laterally, a box-side former carried by said shaft and comprising a plurality of plates 5, arms projecting therefrom, devices carried by the shaft for supporting said arms, and means for conjointly moving said arms longitudinally, 120 means for clamping a box-head to the box-side former, and means for nailing the overlapped portions of the box side together and the box side to said head, substantially as described. 125

19. The combination of a frame, a shaft rotatively carried thereby, means for adjusting the shaft laterally, a box-side former carried by said shaft and comprising a pair of disks

secured to said shaft, arms movably connected with said disks, plates 5 connected with pairs of said arms, means for conjointly moving said arms longitudinally, means for 5 clamping a box-head against said box-side former, and means for nailing the overlapped portions of the box side together and the box side to said head, substantially as described.

20. The combination of a frame, a shaft rotatively carried thereby, means for adjusting the shaft laterally, a box-side former connected with said shaft and comprising a pair of disks secured to said shaft and having radial slots, arms located in said slots and 15 adapted to move longitudinally, teeth carried by said arms, plates 5 connecting pairs of said arms, a sleeve carried by said shaft and adapted to rotate thereon and having worm-threads engaging the teeth of said arms, 20 whereby said arms may be moved longitudinally, means for clamping a box-head to one of said disks, and means for nailing the overlapped portions of the box side together and the box side to said head, substantially as 25 described.

21. The combination of a frame, a shaft rotatively carried thereby, a box-side former connected with said shaft and comprising a pair of disks secured to said shaft and having 30 radial slots, arms located in said slots and adapted to move longitudinally, teeth carried by said arms, plates 5 connecting pairs of said arms, a sleeve carried by said shaft and adapted to rotate thereon and having worm-threads 35 engaging the teeth of said arms, whereby said arms may be moved longitudinally, means for locking said sleeve to said shaft, means for clamping a box-head to one of said disks, and means for nailing the overlapped portions of the box side together and the box side to said head, substantially as 40 described.

22. The combination of a frame, a shaft rotatively carried thereby, a box-side former carried by said shaft and comprising a pair 45 of disks secured to the latter and provided with radial slots, a sleeve located between said disks and having end flanges provided with worm-threads, arms located in said slots 50 and adapted to move longitudinally and provided with teeth to engage the worm-threads, plates 5 carried by pairs of said arms, means for clamping a box-head against one of said disks, and means for nailing the overlapped 55 portions of the box side together and the box side to said head, substantially as described.

23. The combination of a frame, brackets or guides 42 secured therein and each having a vertical slot, bearings or blocks 3 guided to 60 travel in said slots, a shaft 2 journaled in said bearings or blocks, means for preventing endwise movement of said shaft, said brackets or guides each having a threaded aperture, a screw journaled in each of said apertures and pivotally connected with said bearings or blocks so as to suspend the latter, means for rotating said screws, an expandible

box-side former carried by said shaft, means for clamping a box-head to said former, and means for nailing the box while upon said former, substantially as described. 70

24. The combination of a frame, brackets or guides carried thereby and each having a vertical slot, bearings or blocks guided in said slots, each bearing having a recess, each of said 75 brackets having a threaded aperture, a screw journaled in each of said apertures and having a head in the recess of the corresponding bearing or block and a reduced portion or neck, an apertured plate receiving said reduced portion or neck of each screw and secured to the corresponding bearing or block to retain the screw in connection therewith, means for rotating said screws, an expandible box-side former carried by said shaft, means 80 for clamping a box-head to said former, and means for nailing the box while upon said former, substantially as described. 85

25. The combination of a frame, a shaft rotatively carried thereby, a box-side former 90 carried by said shaft and adapted to wind a strip or band upon it, a lever 16 pivotally carried by said frame and having an arm to act upon said strip or band, a lever carried by the first-mentioned lever for operating it, 95 and a rest for the second-mentioned lever, whereby the latter can hold the first-mentioned lever in the operative position, and said arm may be caused to act and be held upon said strip or band, substantially as described. 100

26. The combination of a frame, a shaft rotatively carried thereby, a box-side former carried by said shaft and adapted to wind a strip or band upon it, a lever 16 pivotally 105 carried by said frame and having an arm to act upon said strip or band, a lever 18 pivoted to the lever 16, and a step carried by said frame to receive one end of lever 18, whereby said arm may be caused to act upon said strip 110 or band, substantially as described.

27. The combination of a frame, a shaft carried thereby, a box-side former carried by said shaft, a gate pivotally carried by said frame, means carried by said gate for clamping a box-head to said former and for rotating said head 115 and former, a guide carried by said gate for guiding a hoop as it is wound on the box, and means for nailing the box and the hoop thereto, substantially as described. 120

28. The combination of a frame, a shaft carried thereby, a box-side former carried by said shaft, a gate pivotally carried by said frame, means carried by said gate for clamping a box-head to said former and for rotating said head 125 and former, a guide carried by said gate and having its operative end in the form of a hook with a vertical web adjacent to the box-head for guiding a hoop as it is wound upon said box, and means for nailing the box and the hoop thereto, substantially as described. 130

29. The combination of a frame, a box-side former carried thereby, means for clamping a box-head to said former, a nail-box and plun-

ger, means for moving the same along a box side on the former, and means for moving said nail-box away from the box-side former to permit the latter to rotate relatively to the 5 nail-box, substantially as described.

30. The combination of a frame, a box-side former, a support having an upright, a pair of plates movably connected with said upright and adapted to move longitudinally and a 10 block connecting said plates, with a nail-box carried by said block and having a pair of movable jaws and a pair of bores, one of said bores being adapted to receive nails, a plunger adapted to reciprocate in the other bore, 15 and a block movably guided between said plates and having means to engage said plates, and press the nail-box upon the box side, substantially as described.

31. The combination of a frame, a box-side 20 former, a support having an upright, a pair of plates movably connected therewith so as to slide longitudinally, a block connecting said plates at their lower ends, said plates each having a vertical slot, with a nail-box 25 having a pair of jaws and a pair of bores, one of said bores being adapted to receive nails, a plunger adapted to reciprocate in the other bore, a block located between said plates and having webs located in the slots of said plates, 30 means for reciprocating said block to operate the plunger, and whereby said block may push the nail-box upon the box side, substantially as described.

32. The combination of a frame, a box-side 35 former carried thereby, a nail-box, and means for supporting the same to enable it to move over the box-former, said nail-box comprising a support having an upright, and a head having a pair of jaws and a pair of bores, said head 40 being movably connected with said upright, a tube leading to one bore to deliver nails thereto, a plunger adapted to reciprocate in the other bore, means carried by said support for operating said plunger and adapted 45 to move the nail-box down upon the box side, devices for feeding nails to the nail-box, and means for operating said feeding devices in conjunction with the operation of the plunger, substantially as described.

50. 33. The combination of a frame, a box-side former carried thereby, nailing devices, and means for supporting the same to enable it to move over the box-former, said nailing devices comprising a support having an upright, 55 a pair of plates guided by said upright to have longitudinal movement, a nail-box connected with said plates, said nail-box having a pair of jaws, a pair of bores leading thereto, a tube leading to one bore, a plunger adapted to reciprocate in the other bore, a block carrying 60 said plunger, means for guiding said block on said plates and for enabling said block to move said plates, to press the nail-box upon a box side, means connected with said support for reciprocating said plunger, a funnel connected with said tube, and nail-selecting devices connected with the means that oper-

ate said plunger whereby to operate said nail-selecting devices, substantially as described.

34. The combination of a frame, a box-side 70 former carried thereby, nailing devices, means for supporting said devices and for moving them over the box-side former, said nailing devices having a plunger, a rock-shaft connected with said plunger, nail-selecting devices 75 having a tilting pan, means for conducting nails from the selecting devices to the nailing devices, a crank-arm connected with said rock-shaft, a tilting lever connected with said pan and also connected with said 80 crank-arm, and means for operating said rock-shaft, substantially as described.

35. The combination of a frame, a box-side former carried thereby, a pair of shafts carried by said frame to move longitudinally, 85 nailing devices carried by said shafts, nail-selecting devices also carried by said shafts, said selecting devices having a tilting pan, uprights carried by said shafts, a tilting lever carried by said uprights and connected 90 with said pan, and a crank-arm connected with the nailing devices and with said tilting lever, substantially as described.

36. The combination of a frame, a box-side former carried thereby, a pair of shafts carried by said frame to slide therein, a bracket carried by said shafts, nailing devices carried by said bracket, a rock-shaft connected with said bracket and with said nailing devices, nail-selecting devices connected with said 100 bracket and having a tilting pan, uprights connected with said shafts, a tilting lever carried by said uprights, a link connecting the tilting lever with said pan, a crank-arm connected with said rock-shaft, and links pivotally connected with said crank-arm with said 105 tilting lever, substantially as described.

37. The combination of a frame, a box-side former connected therewith, a gate pivotally connected with said frame, means carried by 110 said gate for clamping a box-head to said former, nailing devices carried by said gate and having a plunger, a lever pivotally carried by said gate and connected with said plunger, and means connected with said lever for rotating the devices that clamp the box-head 115 to the box-side former, substantially as described.

38. The combination of a frame, a box-side former carried thereby, a gate pivotally connected with said frame, box-nailing devices carried by said gate, a lever pivotally carried by said gate and connected with the plunger of the nailing devices, a shaft pivotally carried by said gate and having means to clamp 125 a box-head to the box-side former, and means connecting said lever with said shaft for rotating the latter intermittently as the lever is rocked, substantially as described.

39. The combination of a frame, a box-side 130 former carried thereby, a gate pivotally connected with said frame, nailing devices carried by said gate, a lever pivotally carried by said gate and connected with said nailing de-

5 vices, a shaft rotatively carried by said gate, a disk carried by said shaft to clamp a box side to the box-side former, a ratchet-wheel carried by said shaft, a pawl for operating said ratchet-wheel, and a connection between said pawl and said lever for operating said ratchet-wheel, substantially as described.

10 40. The combination of a frame, a box-side former carried thereby, a gate pivotally connected with said frame, nailing devices carried by said gate, a lever pivotally carried by said gate and connected with said nailing devices, a shaft rotatively carried by said gate, a disk carried by said shaft to clamp a box 15 side to the box-side former, a ratchet-wheel carried by said shaft, an arm loosely hung on said shaft, a pawl pivotally connected with said arm and a rod pivotally connecting said lever with said arm, substantially as described.

15 41. The combination of a frame, a box-side former carried thereby, a gate pivotally connected with said frame, nailing devices carried by said gate, a lever pivotally carried by said gate and connected with said nailing 20 devices, a shaft rotatively carried by said gate, a disk carried by said shaft to clamp a box side to the box-side former, a ratchet-wheel

carried by said shaft, a pawl pivotally connected with said shaft, a rod connecting said pawl with said lever, a bell-crank lever carried by said first-mentioned lever, a rod connecting said bell-crank lever with said pawl, a hand-lever carried by the first-mentioned lever, and a link connecting said hand-lever with the bell-crank lever, substantially as described.

30 42. The combination of a frame, a box-side former carried thereby, a gate pivotally connected with said frame, nailing devices and nail-selecting devices carried by said gate and connected together for delivering nails from the latter to the former, said nail-selecting devices having a tilting pan, a lever pivotally carried by said gate and connected with the nailing devices, means for clamping a box-head to said former, devices connected with said lever for operating said clamping devices, and a connection between said lever and said tilting pan, substantially as described.
